UNITED STATES PATENT OFFICE.

JOHN J. KEARNS, OF SPOKANE, WASHINGTON.

ROTARY SEPARATOR.

Application filed February 14, 1925. Serial No. 9,289.

To all whom it may concern:

Be it known that I, JOHN J. KEARNS, a citizen of the United States, residing at Spokane, in Spokane County, and State of Washington, have invented certain new and useful Improvements in Rotary Separators, of which the following is a specification.

My present invention relates to improvements in rotary separators of the horizontal axis type and designed especially for use in grading seed grain by separation. By the utilization of the apparatus of my invention, sand, gravel and similar materials may be graded by separation in the same manner that the small seed and cracked grain are separated, and therefore it will be understood that while the device is herein described as a grain separator, other materials may be treated thereby.

The invention consists in certain novel features of construction and combinations and arrangements of parts involving a plurality or series of concentric, foraminous screens of differing mesh, adapted to rotate on a single axis and provided with a single charging device and a plurality of discharging devices as will hereinafter be more fully set forth and claimed.

Three grades of grain as coarse, medium, and fine are contemplated in the apparatus as illustrated, and it will be understood that the use of varying numbers of screens are contemplated for the invention.

In the accompanying drawings I have illustrated one complete example of the physical embodiment of my invention wherein the parts are combined and arranged in accordance with the best mode I have thus far devised for the practical application of the principles of my invention.

Figure 1 is a view in side elevation of a rotary separator involving my invention and illustrating by dotted lines the manner of emptying the apparatus.

Figure 2 is an enlarged longitudinal vertical sectional view of the rotary screens partly broken away for convenience of illustration.

Figure 3 is a view in side elevation showing the cylindrical screens and their heads in extended position.

Figure 4 is a view in elevation at the discharge end of the separator.

Figure 5 is a view in elevation at the charging end of the separator.

In the preferred form of my invention the

operating parts are supported on the usual frame 1 which is provided with a hinged journal bearing 2 at the charging end of the machine and a swiveled journal bearing 3 at the discharge end of the machine. This latter bearing has a sleeve 4 with trunnions 5 supported or journaled in the bearing frame 6, and the longitudinally disposed shaft 7 of the machine, is supported or journaled in these two bearings 2 and 3. The shaft is provided with a driving sprocket wheel 8 which is coupled with suitable driving mechanism for the rotation of the shaft.

The shaft carries a pair of circular heads 70 or disks 9 and 10 the former at the charging end of the machine and the latter at the discharging end, and these respective heads have hubs 11 and 12 on the shaft. The heads are adjustable longitudinally of the 75 shaft and set bolts 13 are used in connection with hub 12 for securing the head 10 in adjusted position. The head 9 is held in fixed position on the shaft by means of the nut 14 which engages the threaded portion 80 15 of the shaft provided for the purpose. By relatively adjusting these heads on the shaft the length of the separator may be varied as required to suit different sizes, and because of the peculiar construction 85 involving the heads, this adjustment may be accomplished with facility and a minimum amount of labor.

In the example of the invention herein illustrated three foraminous screens as 16, 17, and 18 are illustrated adapted respectively for separation of coarse, medium and fine seeds, and these screens of varying mesh are arranged concentrically between the two heads, 9 and 10. The screens are in the form 95 of cylinders and they are affixed at the inner sides of the two heads. The head 9 which may be of cast metal is fashioned with a concentric series of annular grooved flanges 19, 20 and 21 at its inner side and the head 10 is fashioned with a complementary series of concentric, annular grooved flanges 19', 20' and 21'. The respective ends of the three cylindrical screens may be provided with annular binding strips or bands 22 105 which fit in the complementary grooved flanges of the two heads for the purpose of supporting the screens between the heads as a rigid structure, rotatable with the shaft.

The head 9 at the charging end of the 110 machine is fashioned with a central charging opening 23 concentric with the shaft 7

and communicating with the interior of the smallest screen 16, and a feed hopper 24 is provided for supplying the grain seed to the interior of the inner or smallest screen. As 5 the separator is rotated it will be apparent that the grain is sifted through the coarse and medium screens and the finest material or dust passes through the outer screen 18. The coarse materials pass out through a central opening 24' in the discharge head 10, and this head is also provided with two concentric annular openings 25 and 26 from the medium and fine screens respectively for material separated in these screens.

15 The central discharge opening 24' and the annular concentric openings 25 and 26 are fashioned with discharge flanges 27, 28, and 29 respectively. These flanges may be cast integral with the head 10 and are located at 20 its outerside as seen in Figures 2 and 4, and these annular flanges flare outwardly from the head for the purpose of guiding the material from the respective screens as the separator rotates. Brace bars 30 are fashioned at both ends of the separator integral 25 with the heads 9 and 10, and as seen in Figures 4 and 5 these bars radiate from the center of the heads to hold the several parts as a rigid structure.

30 In connection with the several discharge flanges of the head 10 I employ a stationary series of discharge spouts 31, 32, and 33 for the coarse, fine, and medium material respectively. These spouts are retained by a band 34 and are each provided with an apron 35 fitted beneath the outer side of the respective flaring flanges 27, 28, and 29. The band partially encircles the several spouts and is attached to a supporting bar 36 by means of 40 bolts 37 Figure 4. The supporting bar is detachably secured on the main frame of the machine by means of bolts 38 and nuts 39 in order that the stationary discharge device including the spouts may be readily removed 45 from the separator when required.

After the seed grain has been thoroughly separated by the operation of the rotary screens, and the several grades of material have been disposed of through the several 50 spouts and emptied into bags or other receptacles, the shaft and its screens may be

tilted to the position indicated in dotted lines for the purpose of emptying the residue from the separator.

For this purpose the hinged journal bearing 2 is opened to permit tilting of the separator on the trunnions 5 of the swiveled bearing, and a sleeve 40 may be slipped over the end of the shaft, as indicated in Figure 1 to retain the separator in tilted position. 55 This sleeve is attached to a cord or flexible wire 41 which is secured at 42 to the machine frame, and the separator is held in tilted position for cleaning its interior.

In this tilted position, the screens may be 60 changed with facility, by first releasing the several screens from the spaced heads. Screens of differing mesh and of differing length may readily be interchanged for various purposes, while the separator is in tilted 65 position, and after proper adjustment of parts the separator is returned to normal level position for subsequent operation.

Having thus fully described my invention 70 what I claim as new and desire to secure by Letters Patent is—

1. A rotary separator comprising a shaft and a pair of spaced heads thereon, a concentric series of screens forming annular spaces with one closed end, a complementary series of grooved annular flanges on adjoining faces of said heads for said screens, means for securing the heads on the shaft, a central charging opening in one head and a central discharging opening in the other 85 head, and a series of annular discharge openings complementary to said spaces surrounding the last mentioned central opening.

2. A rotary separator comprising a shaft, a pair of spaced heads and means for securing said heads on the shaft, a concentric series of grooved annular flanges on adjoining faces of said heads, a series of foraminous screens retained in said grooved flanges and forming annular spaces, one of said heads having a central charging opening and a central discharging opening in the other head, and a series of outwardly flaring discharge flanges located adjacent to annular discharge openings in the second head. 95

In testimony whereof I affix my signature.
JOHN J. KEARNS.
